CLAIM

I claim the ornamental design for a scaffold clamp, as shown.

DESCRIPTION

FIG. 1 is a front, right side, and bottom perspective view of a scaffold clamp;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front, right side, and bottom perspective view of a second embodiment of a scaffold clamp; and,

FIG. 9 is a front, right side, and bottom perspective view of the scaffold clamp.

The broken lines are for illustrative purposes only and form no part of the claimed design.
